1 Claim

This invention relates to a new and distinct variety of Chrysanthemum plant which is a sport of Dark Pinnacle, 10 Ser. No. 392,953 and filing date Aug. 30, 1973.

This sport was selected from a flowering in my commercial greenhouses in Mountain View, Calif., because of its bronze color as compared to Dark Pinnacle which is a dark pink color. The plant was revegetated and through repeated flowering, the growth and response time proved to be the same as Dark Pinnacle. Flowering during the heat of summer resulted in a lighter bronze color.

This new sport is similar to Dark Pinnacle in the following characteristics:

1. Foliage,
2. Size of flower,
3. Heavy stem and growth,
4. Short growth, and
5. Flowering response.

This new selection is different from Dark Pinnacle in the following way: Bronze color.

Asexual reproduction of my new and distinct variety has proven to be consistent in:

1. Vegetative growth, and
2. Claims of flower characteristics.

The overall growth characteristics may vary according to environmental conditions under which it is grown, however, here in the Bay Area of California it has a response period of approximately seven and one-half (7½) weeks and is suggested for blooming from October through June.

The accompanying drawing illustrates the color as being as true as possible with color illustrations of this type. The color of the new variety will be apparent in the photograph.

The color designation is by use of the Royal Horticulture Society color chart, R. F. Wilson, of the Royal Horticulture Society of London, England.

Plant:

Botanical classification: *Chrysanthemum morifolium* Ramat.
Origin: Selected from a flowering in commercial greenhouses.
Form: Herbaceous.
Height: 90 to 100 centimeters.
Growth: Strong; vigorous; upright.

	Dark Pinnacle	Bronze Pinnacle
Leaf:		
Size	16.2 cm. x 10 cm. (avg.)	16.2 cm. x 10 cm. (avg.)
Shape	Ovate, deeply lobed	Ovate, deeply lobed
Texture	Smooth, finely pubescent	Smooth, finely pubescent
Ribs and veins	Prominent	Prominent
Margin	Deeply lobed	Deeply lobed
Color	Yellow Green, 147/A	Yellow Green, 147/A
Bud:		
Diameter	3.4 cm	3.4 cm.
Depth	2.5 cm	2.5 cm.
Color	Red Purple, 74/D	Greyed-Orange, 168/D.
Flower color:		
Center of flower	Red Purple, 73/D	Yellow Orange, 21/D.
Base of petal	Red Purple, 74/D ($\frac{3}{4}$ " from end)	Greyed Red, 179/D.
Inside of petal	Red Purple, 74/B	Gray Red 179/B.
Reverse of petal	Purple, 75/C	Yellow, 11/C.
Tonality from distance	Red Purple, 74/C	Orange Red, 34/D.
Other characteristics:		
Size of flower	13.5 cm. x 8.84 cm	14 cm. x 9 cm.
Stamens	Numerous	Numerous
Pollen	None visible	None visible
Pistil	Present	Present

I claim:

1. A new and distinct variety of Chrysanthemum plant having the characteristics of a bronze flower.
